SECURED SISTER-HOOK ASSEMBLY
 Herman G. Alofs, 1512 Yorkshire SE.,
 Grand Rapids, Mich.
 Filed Sept. 30, 1963, Ser. No. 312,581
 5 Claims. (Cl. 24—165)

This invention relates to the construction of coupling devices, and has been developed primarily to connect an automobile safety-belt to a floor terminal. The invention utilizes a type of connector commonly referred to as a "sister-hook," which involves a pair of plates having hook formations such that the plates can be placed "back-to-back," with the hooks partially superimposed to define an opening. Each of the hooks then has a portion covering the opening of the other hook.

The opposite end of the plates (from the hooks) is normally adapted to receive a loop of belting. The hooks can be separated to admit a terminal member, and subsequent belt tension will be effectively transferred to the terminal. The problem with this type of device arises on the advent of subsequent slack conditions in the belt. Vibrations and random belt positions can easily permit the hook plates to separate enough to disengage from the terminal. The security of the safety-belt is then lost. The present invention has been developed as a means for preventing accidental separation of the plates, without impairing the utility and intended disengageability of the coupling.

The preferred form of the invention incorporates a spring device in the form of an axially-projected C-shaped cross-section of the type frequently encountered in large pivoted paper clips. The plates are received in the opening of the C, and the separation of the hooks (to admit a terminal fitting) is resisted by the resilience of the spring. The several features of the invention will be analyzed in detail through a discussion of the particular embodiments illustrated in the accompanying drawing, in which:

FIGURE 1 is a perspective view of a fully assembled and locked device incorporating the present invention.

FIGURE 2 is a sectional elevation on the plane 2—2 of FIGURE 1, on a somewhat enlarged scale.

FIGURE 3 is a perspective view of a modified form of the invention.

FIGURE 4 is a sectional elevation on a plane 4—4 of FIGURE 3.

Referring to FIGURES 1 and 2, the plates generally indicated at 10 and 11 are provided with the hook portions 12 and 13, respectively, which are superimposed so that the hook portions together define an opening 14.

The plate 10 is provided with the slots 15, 16, and 17, and the plate 11 with the slot 18. The belt 19 is interengaged with these slots in the manner best shown in FIGURE 2, which illustrates the belt in slack condition. Application of tension to the portion 20 of the belt will result in constricting the belt around the portions of the plates 10 and 11 between the slots 15—18.

The plates are biased to the "closed" conditions shown in FIGURES 1 and 2 by the action of the spring 21. This spring is received in the slots 15 and 18 of the plates, and bears upon the plates at a point displaced from the edge of the slot. The plates 10 and 11 are provided with the offsets 22 and 23, respectively, to provide a tendency to maintain the spring 21 in the illustrated position to avoid interference with the belt as it passes through the slots 15 and 18. It will be obvious that the separation of the hooks 12 and 13 in a direction normal to the surface of the plates will induce an opening of the C-shaped cross-section of the spring 21, resulting in a resilient deformation of the spring

2

and the application of a biasing action tending to return the plates to the closed position. The formation of the spring 21 is such that some degree of biasing is applied to the plates even in the closed position.

5 In the event that it becomes desirable to further lock the plates together, or to lock them without the use of a spring 21, holes along the axis of symmetry of the plates 10 and 11 are provided for receiving a cotter pin 24. At least the right-hand end of the plates 10 and 11 may then be formed on the same die, so that the inversion of the plates to establish the back-to-back relationship shown in FIGURES 1 and 2 will result in the alignment of the holes for receiving the cotter pin 24.

The modification shown in FIGURES 3 and 4 involves the use of identical plates 25 and 26. These plates are provided with the hooks 27 and 28, and with the slots 29 and 30 for receiving the loop 31 of the belt 32. The plates are also provided with the offsets 33 and 34 for positioning the spring 35, and it will be noted that the plates also have the holes 36 and 37 on the axis of symmetry. These holes may be utilized for receiving a cotter pin as previously described.

The offsets 22—23 and 33—34 may take a variety of forms, such as the preferred continuous ridge shown in the drawings, or these may be one or more isolated dimples or lanced portions of the material of the plates. Practically any form of projection will serve to position the spring 33 in the manner illustrated so that interference with the belting is avoided. The amount of discontinuity, or gap, in the springs 21 and 35 will be determined by the proportions of the device being constructed, and will also be a function of the thickness of material of the spring and of the amount of deflection that is desirable.

35 The particular embodiments of the present invention which have been illustrated and discussed herein are for illustrative purposes only, and are not to be considered as a limitation upon the scope of the appended claims. In these claims, it is my intent to claim the entire invention disclosed herein, except as I am limited by the prior art.

I claim:

1. A sister hook assembly, comprising:

two similarly formed plates each having a hook portion and at least one slot for receiving belt means, said plates being normally positioned in opposite relationship whereby said hook portions overlap and define together an opening,

said plates having a ridge adjacent said slot along the side thereof toward said hook portion, and a C-shaped spring extending through said slots and having a gap, said spring receiving said plates in clamping relationship at said gap whereby separation of said hook portions causes resilient expansion of said spring and increase of said gap,

said spring bearing on said plates on the opposite side of said ridge from said opening to maintain said spring close to the adjacent edge of said plate at said opening to avoid interference with said belt means.

2. A sister hook assembly, comprising:

two plates each having a hook portion and at least one slot for receiving belt means, said plates being normally positioned in opposite relationship whereby said hook portions overlap and define together an opening,

at least one of said plates having a lateral projection adjacent said slot; and

a C-shaped spring extending through said slots and having a gap, said spring receiving said plates in clamping relationship at said gap whereby separa-

tion of said hook portions causes resilient expansion of said spring and increase of said gap, 5
said spring bearing on said plates on the opposite side of said projection from said opening to maintain said spring close to the adjacent edge of said plate at said opening to avoid interference with said belt means.

3. A safety belt and sister hook assembly, comprising: safety belt means; two plates each having a hook portion and at least one slot receiving said belt means, 10
said plates being normally positioned in opposite relationship whereby said hook portions overlap and define together an opening,

said plates each having a hole, said holes being 15
normally in alignment;

a C-shaped spring extending through said slots and having a gap, said spring receiving said plates in clamping relationship at said gap whereby separation of said hook portions causes resilient expansion of 20
said spring and increase of said gap; and

4. A safety belt and sister hook assembly, comprising: safety belt means; two plates each having a hook portion and at least one slot receiving said belt means, 25
said plates being normally positioned in opposite relationship whereby said hook portions overlap and define together an opening;

a C-shaped spring extending through said slots and having a gap, said spring receiving said plates in clamping relationship at said gap whereby separation 30
of said hook portions causes resilient expansion of said spring and increase of said gap.

5

5. A safety belt and sister hook assembly, comprising: safety belt means; two plates each having a hook portion and at least one slot receiving said belt means, 5
said plates being normally positioned in opposite relationship whereby said hook portions overlap and define together an opening;

a spring retained on and engaging said plates and biasing the same together; and said plates including means retaining said spring located in its biasing engagement with said plates, whereby temporary separation of said hook portions causes resilient deformation of said spring for attachment and detachment of said hook portions.
